DESIGN FOR A TOY TANK PUZZLE

Allen R. Ridley, Burbank, Calif.

Application November 22, 1944, Serial No. 116,490

Term of patent 14 years

(Cl. D34—15)

To all whom it may concern:

Be it known that I, Allen R. Ridley, a citizen of the United States of America and a resident of the city of Burbank, in the county of Los Angeles and State of California, have invented a new, original, and ornamental Design for a Toy Tank Puzzle, of which the following is a specification, reference being had to the accompanying drawing, forming part thereof.

In the drawing:

Figure 1 is a side elevational view of a toy tank puzzle, showing my new design,

Figure 2 is a rear elevational view,
Figure 3 is a front elevational view,
Figure 4 is a top plan view, and
Figure 5 is a bottom plan view.

The opposite side of Fig. 1 is the same as shown in Fig. 1.

I claim:

The ornamental design for a toy tank puzzle, substantially as shown and described.

ALLEN R. RIDLEY.
